[57] CLAIM

The ornamental design for a projection television receiver, as shown and described.

DESCRIPTION

FIG. 1 is a front, top and right side perspective view of a projection television receiver showing our new design;

FIG. 2 is a left side elevational view thereof;

FIG. 3 is a front elevational view thereof;

FIG. 4 is a top plan view thereof;

FIG. 5 is a bottom plan view thereof;

FIG. 6 is a rear elevational view thereof;
FIG. 7 is a view like FIG. 1 of another embodiment of a projection television receiver showing our new design wherein a door is added;

FIG. 8 is a left side elevational view thereof;

FIG. 9 is a front elevational view thereof;

FIG. 10 is a top plan view thereof;

FIG. 11 is a bottom plan view thereof;

FIG. 12 is a rear elevational view thereof; and

FIG. 13 is a view like FIG. 7 thereof with the door open.
